UNITED STATES PATENT OFFICE.

WILLIAM BROAD, OF BEAVER FALLS, PENNSYLVANIA, ASSIGNOR OF THREE-FOURTHS TO HARRY E. McLAIN, OF PITTSBURGH, PENNSYLVANIA.

SPARK-INTENSIFIER.

1,391,239.

Specification of Letters Patent. Patented Sept. 20, 1921.

Application filed September 30, 1920. Serial No. 413,939.

To all whom it may concern:

Be it known, that I, WILLIAM BROAD, a citizen of the United States, and a resident of Beaver Falls, in the county of Beaver 5 and State of Pennsylvania, have invented a new and useful Improvement in Spark-Intensifiers, of which the following is a specification.

The invention relates to automobiles 10 which are provided with internal combustion engines for propelling them, and has particularly to do with the ignition for such engines.

It has been proposed to connect an electric condenser to an ignition circuit between the source of electrical supply and the engine for the purpose of producing larger ignition sparks. The difficulty experienced with such use of a condenser is that the ignition 20 is not benefited during all conditions of service.

The spark which results from the use of a condenser is thicker and hotter than a spark produced under similar conditions 25 without a condenser, and, because of its increased thickness and greater heat, the spark effects a more nearly complete combustion of an explosive charge. However, it has been found that, in using a condenser, 30 there will frequently be no spark when there is abnormally high compression in the engine cylinder. It appears that the current modified by a condenser does not have sufficient strength to cause a spark to jump 35 from one terminal to another of a spark plug when the medium through which the spark must pass is highly compressed or condensed.

The condition under which the ignition 40 will so fail is chiefly, if not solely, when a car is ascending a hill and particularly when the engine is running at high speed and transmission is through a low gear train. During normal running conditions, such as 45 when running on level ground or ascending an incline which is not sufficiently steep to demand extraordinary power from an engine, the condenser-modified sparks effect such complete and certain combustion of the 50 fuel that greatly increased mileage per unit volume of fuel results. However, the advantage thus gained by the use of a condenser is largely offset when traveling through hilly country because of frequent failures to ignite, 55

The object of the invention is to provide, for an automobile of the type contemplated herein, a condenser which will become automatically disconnected from the ignition circuit while the automobile is ascending what 60 may be designated as a steep hill, and which will be automatically restored or again connected to the ignition circuit when the automobile proceeds on level ground or a hill of 65 low grade.

The invention is illustrated in the accompanying sheet of drawings of which Figure 1 is a plan view of a condenser attached to an automobile; Fig. 2, a vertical central sectional view of the condenser, the plane 70 of view being indicated by line II-II, Fig. 1; Fig. 3, a diagrammatic representation of an ignition circuit for an automobile and condenser connected to the circuit; and Fig. 4, a side view of a portion of an automobile 75 illustrating the general position of the condenser with relation to the automobile.

In the practice of the invention, a condenser is electrically connected to an ignition circuit between the source of electric current 80 supply and an internal combustion engine of an automobile, and means are provided for automatically disconnecting the condenser from the circuit when the automobile ascends a steep hill. As far as some features of the invention are concerned, the 85 condenser may be of any desired type of construction and it may be attached at various points to the ignition circuit. If desired, a single condenser may be used for 90 the entire circuit or a separate condenser may be connected to each of the several conductors leading to the spark plugs. While various means may be used for automatically disconnecting the condenser from 95 the circuit, it is preferred to use a gravity switch for this purpose.

In the illustrative embodiment of the invention, the condenser and the gravity switch for disconnecting it from the ignition 100 circuit are, for simplicity in construction, cheapness in cost and effectiveness in operation, combined in a single structure, the preferred form of which is illustrated in detail in Fig. 2. The structure includes a 105 central tube 1 of insulating material which may be closed at one end by a cap 2 of insulating material and at its other end by a metal cap 3. The condenser is formed upon and the switch within such tube, the con- 110

denser elements comprising a pair of separately insulated conducting wires 4 and 5 wound spirally and adjacent to each other upon the tube. One of the condenser elements, in this case the conducting wire 4, is electrically connected to one terminal of the gravity switch, which terminal is illustrated as consisting of a metal sleeve 6 arranged within the tube 1. The other end of the wire 4 is adjacent to, but not in contact with the metal cap 3. The second of the condenser elements, namely, the conducting wire 5, is electrically connected at 7 to the metal cap 1, through which it may be grounded, and extends spirally upon the tube 1 to a point adjacent to the cap 2. Thus, each of the condenser elements has but a single electrical connection to a conducting member, the condenser element 4 being connected only to the switch terminal 6 and the element 5 to the metal cap 3. When functioning as a condenser, the insulation of the wires 4 and 5 serve as the dielectric between the two conductors.

Having reference now to the gravity switch illustrated herein, one terminal thereof comprises the sleeve 6, as previously explained, and the other terminal is formed by the head of a screw 8 which extends through the central portion of the cap 2. The movable member of the switch is a metal ball 9, which, in the full line position indicated in Fig. 2, affords a path of electrical continuity between the screw 8 and the sleeve 6. The screw 8 may be suitably connected to a conductor or lead 10 whereby the condenser may be electrically connected to an ignition circuit. For connecting the conductor 10 to the screw 8, a metal sleeve 11 may be soldered or sweated upon the exposed adjacent ends of such members, and thereafter, the pocket formed in the end of the cap 2 may be sealed by wax or other suitable material. The condenser may be inclosed in a tube 30 of insulating material, to which tube the end caps 2 and 3 are attached.

When installed, the combined condenser and switch structure is attached to an automobile in such position that the axis of the structure extends longitudinally of the automobile and is inclined downwardly from the general horizontal line of extent of an automobile, the cap 2 of the structure being foremost. This general position of the structure is diagrammatically represented in Fig. 4, which shows the axis 12 thereof as inclined downwardly from the general horizontal line of extent 13 of an automobile 14. In this figure the condenser and switch structure is illustrated to a much larger scale than is the automobile. In actual construction the condenser and switch may, by way of example, be two or three inches long and it may be attached to any suitable part of

an automobile provided its general position with relation to the automobile is such as indicated in Fig. 4.

As long as the automobile is running on a roadway, which, due to its grade or inclination, maintains the axis 12 inclined below the horizontal, the ball 9 will maintain closed the circuit through the conductor 10 and the condenser element 4, and hence during such time the condenser will be electrically connected to the ignition circuit. When the automobile ascends a hill of such inclination that the switch axis 12 inclines above the horizontal, the ball 9 will roll to the rear end of the tube 1, thereby breaking the circuit between the screw 8 and sleeve 6, and hence cutting the condenser out of circuit. Thus, the condenser may be maintained in electrical connection with the ignition circuit until such time as the engine of the automobile is required to run under the condition which most frequently results in high cylinder pressure. When this condition arises, the condenser becomes automatically disconnected from the ignition circuit.

For different automobiles and for different road conditions, the most advantageous inclination to the horizontal of the switch axis 12 will vary. To the end that the position of the switch may be readily adjusted to that which is most advantageous, the condenser and switch structure is preferably attached to an adjustable bracket, which, as illustrated in Figs. 1 and 2, may comprise arms 15 and 16 pivotally connected to each other by a bolt 17 and thumb nut 18. The arm 15 may be connected to the metal cap 3 by means of a screw 19, and the arm 16 to a suitable metal part 20 of the automobile by means of screws 21. By such connections, the condenser element 5 may be suitably grounded. The bracket 15, 16 may be constructed of metal having sufficient resiliency to minimize the effect upon the switch of the vibrations of the automobile.

In Fig. 3 there is diagrammatically represented one way of installing the condenser in an ignition circuit. In the figure there is indicated a source of electrical energy which may be a magneto 22, a timer 23 connected by a conductor 24 to the magneto, and an engine 25, the spark plugs of which are connected by conductors 26, 27, 28 and 29 to the several terminals of the timer. A single condenser is here shown as being electrically connected, through conductor 10 to the conductor 24 leading from the dynamo 22 to the timer 23, the condenser serving to modify the sparks of each of the several spark plugs of the engine. It will be understood, however, that the condenser may be installed otherwise than as indicated in Fig. 3 and that, if desired, more than one condenser may be used.

According to the provisions of the patent

statutes, I have described the principle and operation of my invention, together with the structure which I now consider to represent the best embodiment thereof. However, I desire to have it understood that, within the scope of the appended claims, the invention may be practiced by other forms of construction than that specifically shown, and described herein.

10 I claim:

1. The combination with an automobile provided with an internal combustion engine for propelling it, a source of electric current supply, and an ignition circuit between the engine and current supply; of a condenser electrically connected to said circuit, said connection including a gravity switch adapted to disconnect the condenser from the circuit when the automobile ascends a hill.

2. The combination with an automobile provided with an internal combustion engine for propelling it, a source of electric current supply, and an ignition circuit between the engine and current supply; of a condenser electrically connected to said circuit, said connection including a movable circuit closer automatically movable from circuit closing position when the automobile ascends a hill.

3. The combination with an automobile provided with an internal combustion engine for propelling it, a source of electric current supply, and an ignition circuit between the engine and current supply; of a condenser electrically connected to said circuit, said connection including a switch having a pair of terminals, a guide adjacent to said terminals and inclined to the longitudinal line of extent of the automobile, and a switch-closing element movable in said guide under the force of gravity, whereby the condenser becomes automatically dis-

connected from said ignition circuit when the automobile ascends a hill.

4. The combination with an automobile provided with an internal combustion engine for propelling it, a source of electric current supply, and an ignition circuit between the engine and current supply; of a condenser electrically connected to said circuit, said connection including a switch having a pair of terminals, a guide adjacent to said terminals and inclined to the horizontal line of extent of the automobile, a switch-closing element movable in said guide under the force of gravity, and means for adjusting the inclination of said guide.

5. An electric condenser comprising a tube closed at its ends, a contactor arranged centrally of the tube at one end thereof, a second contactor within and attached to the wall of said tube, a condenser element electrically connected to one of said contactors, and a circuit closing member movable in said tube to and from a position closing a circuit through said contactors.

6. An electric condenser comprising a tube closed at its ends, two electrically disconnected insulated conductors wound spirally upon said tube and forming a pair of condenser elements, a contactor arranged centrally of the tube at one end thereof, a second contactor within and attached to the wall of said tube and electrically connected to one of said condenser elements, and a ball of electrical conducting material movable in said tube to and from a position closing a circuit through said contactors.

In testimony whereof, I have hereunto set my hand.

WILLIAM BROAD.
